US00D541974S

(12) **United States Design Patent** (10) **Patent No.:** **US D541,974 S**
(45) **Date of Patent:** **** May 1, 2007**

(54) **LIGHT FIXTURE**

(76) Inventor: **Aihui Yuan**, Room #1305, Winnerway Hotel, Dong Guan City, Guang Dong Pro (CN)

(**) Term: **14 Years**

(21) Appl. No.: **29/263,771**

(22) Filed: **Jul. 28, 2006**

(51) **LOC (8) Cl. 26-03**

(52) **U.S. Cl. D26/87; D26/92**

(58) **Field of Classification Search** D26/72, D26/80-92; 362/147, 362, 363, 370, 371, 362/431, 432, 806

See application file for complete search history.
